UNITED STATES PATENT OFFICE

ROY W. JOHNSON, OF DETROIT, MICHIGAN, ASSIGNOR TO C. M. HALL LAMP COMPANY,
OF DETROIT, MICHIGAN, A CORPORATION OF MICHIGAN

LAMP SOCKET

Application filed August 6, 1928. Serial No. 297,736.

The invention relates to lamp sockets for vehicle headlamps and the like, and more particularly to a socket construction applicable to a lamp where accurate positioning is desired. While the invention may be applied to a lamp having means for adjusting the focus thereof, it is particularly advantageous in a headlamp of the so-called fixed focus type, since in the latter case it is necessary to have a construction wherein the interchange of lamp bulbs can be made while maintaining for every exchanged bulb a close tolerance for the maximum permissible variation between the actual filament location and the theoretically correct position.

The primary object of the invention is to provide a socket construction adapted to maintain the lamp bulb firmly within the socket member without permitting lateral deflection.

A second object is to provide a socket construction having not only the usual retainer for the base of the lamp bulb, but also additional means for supporting the bulb itself in such a way as to maintain the filament in fixed relation to the axis of the lamp within close limits of tolerance.

Another object is to provide a lamp of the fixed focus or non-adjustable focus type wherein the interchangeable lamp bulbs are all held in accurate relation to the focal point of the lamp within such close limits of tolerance as to render the fixed focus type of lamp practical for vehicle headlights.

These and other objects are attained by the novel construction hereinafter more fully described and illustrated in the accompanying drawings, wherein

Figure 1 is a longitudinal section through the socket;

Figure 2 is an end view of the socket;

Figure 3 is a perspective view with portions cut away to reveal certain features of construction.

The drawings illustrate a fixed focus sock-

et construction wherein 1 is the reflector of the lamp and 2 the outer sleeve of the socket which is permanently attached thereto by suitable means such, for example, as clinching the metal of the sleeve to the reflector as 50 indicated at 3. At the opposite end of the outer sleeve there is preferably provided an inwardly turned annular flange 4 forming a seat for a coil spring 5. 6 represents the bulb retainer member which may be of a 55 conventional type and is illustrated in the drawings as such. Thus the bulb retainer 6 is tubular and has at the rear end thereof the inturned annular flange 7 for engaging the insulating core 8. This core is provided 60 with the two apertures 9 therethrough for slidably receiving the contact rods 10. The contact portions 11 at the ends of the rods are enlarged and form abutments for the contact springs 12, the other ends of which 65 rest against the shoulders 13 in the core at the base of the recessed portions 14. The outer end of the bulb retainer has a plurality of J slots 15 formed therein adapted to receive the projecting pins 16 of the lamp bulb 70 stem or base 17 in the usual manner. 18 represents the lamp bulb in its entirety, consisting of the bulb base 17 aforementioned and the bulb 19. The filaments are fixedly supported within the bulb, and in the construction illustrated there are two filaments 20 and 21 spaced vertically from each other. The lamp bulb may be inserted within the bulb retainer in the usual manner by causing the pins 16 to engage the J slots, that is, 75 by pressing the bulb axially and giving a slight turning movement thereto.

With bulb retainers of the type illustrated it has been found in commercial practice that the bulb is not rigidly held within the retainer but has a slight movement in all directions due to the fact that there is always a slight clearance between the base 17 and the inner surface of the bulb retainer 6 to permit of the easy exchange of the lamp bulbs. 80 85 90

The amount of displacement of the bulb filaments is sufficiently great to materially affect the focus of the headlamp.

My invention contemplates a construction adapted to prevent this deflection or, at least, to minimize the same to such an extent that it will not throw the lamp enough out of focus to interfere with the successful operation of a fixed focus type of lamp. My construction consists in the arrangement of a sliding or telescoping sleeve 22 surrounding the bulb retainer 6 and yieldably engaging the bulb 19 at a point beyond the base thereof. This telescoping member 22 is therefore preferably flared at its outer end as indicated at 23 in order to form a surface extending at substantially the same angle as the glass of the bulb at the point of contact. The sleeve 22 is arranged between the outer sleeve 2 and the tubular bulb retainer 6. The sleeve has an annular inturned flange 24 engaging the spring 5.

In a fixed focus socket the bulb retainer 6 must be rigidly or fixedly mounted with respect to the reflector and in the present construction this is accomplished by the use of a locking spring 25, the end 26 of which passes through a slot 27 in the outer sleeve 2, a slot 28 in the telescoping sleeve 22 and a slot 29 in the tubular bulb retainer 6. The slots 27 and 29 are of such size as to closely fit the portion 26 which therefore accurately positions the outer sleeve with reference to the inner bulb retainer. The slot 28 in the telescoping sleeve is elongated sufficiently to permit said telescoping sleeve to have sliding movement without having interference with the portion 26.

With the construction as described above, the telescoping sleeve 22 serves as an additional support for the lamp bulb, thus preventing wabbling of the bulb in any direction. It also maintains a resilient pressure upon the bulb in an axial direction, thus insuring that the pins 16 on the bulb base will be held in the most forward position permitted by the J slots of the bulb retainer. The sleeve, furthermore, holds the glass of the bulb in exact predetermined position with respect to the lamp socket and the lamp reflector. Thus by having all interchangeable lamp bulbs so constructed the portion of the bulb engaging with the telescoping sleeve is in accurate predetermined relation to the filaments of the bulb, the improved socket construction herein described is also useful for maintaining the filaments of interchangeable lamp bulbs in exact predetermined relation with the reflector. This relationship of the filaments to the base of the glass portion of the bulb can be maintained within very close limits and by inspecting each bulb to insure that it comes within the limited tolerance set for this particular dimension it is possible with my improved socket construction to

manufacture on a commercial scale a fixed focus headlamp that will meet with the requirements for a safe headlight.

It is to be understood that while my invention is particularly adapted for fixed focus lamps, it is not necessarily limited to this use for in its broader aspects the invention contemplates the provision of means for supporting the lamp bulb to prevent deflection thereof regardless of whether or not the lamp is provided with means for adjusting the focus.

What I claim as my invention is:

1. In a lamp, a reflector, a sleeve fixedly secured to said reflector, a bulb retainer member fixedly secured to said sleeve, a bulb carried by the retainer member, a second sleeve intermediate said first sleeve and retainer member and having a bulb engaging portion, and means for resiliently urging the bulb engaging portion of said second sleeve into engagement with said bulb. 80

2. In a lamp, a reflector, a sleeve rigid with the reflector, a bulb retainer member within the sleeve and rigid therewith, a lamp bulb carried by but movable relative to said member, and a second sleeve between said first mentioned sleeve and member and movable relative thereto into engagement with the bulb. 90

3. In a lamp, a reflector, a sleeve rigid with the reflector, a bulb retainer member within the sleeve, a lamp bulb carried by the member, a second sleeve between the first sleeve and member, and a connection between said first sleeve and member passing through the second sleeve but permitting it to move relative to the other parts into engagement with the bulb. 100

4. In a lamp, a reflector, a sleeve rigid with said reflector, a bulb retainer member within said sleeve, an element connecting said member to said sleeve whereby said member is held against movement relative to said sleeve, a bulb carried by said member, a second sleeve slidable between said member and first sleeve having a slot receiving said element and having a portion engaging with said bulb, and means between portions of said first and second sleeves holding the latter against said bulb. 105

5. In a lamp, a reflector, a sleeve rigid with said reflector, a bulb retainer member within said sleeve, an element connecting said member to said sleeve whereby said member is held against movement relative to said sleeve, a bulb carried by the member, a second sleeve slidable between said member and first sleeve and having a flared portion engaging the bulb to position the same relative to the reflector, and yieldable means engaging the second sleeve and holding the flared portion thereof in engagement with the bulb. 115

6. In a lamp, a reflector, a sleeve rigid with
said reflector, a bulb retainer member within
in the sleeve, a bulb in the member, a second
sleeve slid able between said member and first
sleeve and engageable with the bulb to pos-
5 tition the same relative to said reflector, and
a connection between the member and first
sleeve including means extending through
the second sleeve permitting sliding move-
10 ment of said second sleeve but preventing
movement of said member relative to said
first sleeve.

In testimony whereof I affix my signature.
ROY W. JOHNSON.
